UNITED STATES PATENT OFFICE.

ARTHUR MOTT WORD, OF ROME, GEORGIA, ASSIGNOR TO THE TOWERS & SULLIVAN MANUFACTURING COMPANY, OF SAME PLACE.

HARROW.

SPECIFICATION forming part of Letters Patent No. 352,284, dated November 9, 1886.

Application filed April 17, 1886. Serial No. 199,225. (No model.)

To all whom it may concern:

Be it known that I, ARTHUR MOTT WORD, a citizen of the United States, residing at Rome, in the county of Floyd and State of Georgia, have invented certain new and useful Improvements in Harrows; and I do hereby declare the following to be a full, clear, and exact description of the invention, such as will enable others skilled in the art to which it appertains to make and use the same.

My invention relates to harrows, and is particularly well adapted to side harrows, and has for its object to provide improved means for the ready and easy adjustment of the teeth and their standards to different positions nearer to or farther removed from the draft pole or beam or draft-line on the harrow, so as to regulate the width of the harrow, as will appear hereinafter.

20 In the drawings, Figure 1 is a plan view of the harrow; Fig. 2, a side elevation thereof; Fig. 3, a perspective thereof.

The letter A designates the pole or beam, having pivoted thereto by suitable means—for instance, by bolts B at right angles to it—one or more cross-bars, C, preferably of metal, two cross-bars being shown, which lie under the beam.

To the cross-bars C are secured the curved standards E, to which the points F are affixed. These standards are curved back of the rear cross-bar C, and extend from the rear to the front cross-bar and lie under both bars. The two outer standards are jointed to the rear cross-bars by bolts B² and to the front cross-bar by bolts B', while the middle standard is pivoted to the beam by the same bolts, B, that secure the cross-bars to the beam. By such construction, when the cross-bars are turned on their 35 pivotal connections, the end standards will be adjusted on their pivotal connections, so as to assume a parallel position with the line of draft, as shown by dotted lines in Fig. 1, and will be brought nearer to the beam, so that the width 40 of the harrow will be narrowed proportionately to the adjustment.

By placing the cross-bars beneath the beam and the standards beneath the cross-bars the bars are more strongly connected and braced 45 to the beam by the central standard than when otherwise arranged, and the draft on the curved

portion of the standards is taken from off the pivots and thrown more directly up against the cross-bars, so that as a consequence the parts can be made lighter without detracting from 55 their strength.

The adjustment of the cross-bars and standards is effected by means of a curved bar, D, which lies under the beam, and is secured to the front cross-bar C by means of the same 60 bolts, B', that secure the standards thereto. The advantage of such arrangement is that when the standards are to be adjusted the leverage is applied direct to the pivotal connection at both ends of the cross-bar, so that there is less 65 liability of the joint binding, and it will thus be made to adjust easier. Furthermore, it obviates the necessity of extra bolts, and also brings the leverage more directly on the standards at both ends of the cross-bar. The ad- 70 vantage of placing the curved bar under the beam is that any upward strain is thrown upon the beam instead of upon the bolts, and a firmer connection can be made than when the rod is passed over the beam.

I prefer to bind the curved bar to the beam by a clamp-bolt, G, of any suitable construction—for instance, as shown in the drawings—which is held by nuts d, between which and the beam a plate, H, is preferably interposed. 80 By such construction the curved bar can be made lighter, and the adjustment can be more quickly and easily effected and made to a greater nicety than when the bar is clamped by a bolt passed through holes in the bar, as 85 shown in Fig. 1. The handles I are bolted to the beam, as shown.

My object is to provide a simple, light, and yet strong harrow in which the parts can be quickly and easily adjusted and the strain on 90 the parts will be distributed to the best advantage, and so I have constructed the parts as described. I wish to be understood, however, as making no claim to a plow with cross-bars having standards bolted thereto and adjustable to bring the standards nearer to or farther from the beam to regulate the width of furrow, as I am aware that such, broadly, is not new; but,

Having described my invention and set forth 100 its advantages, what I claim is—

In a side harrow such as described, the com-

bination, with the beam, cross-bars C, and middle standard E, pivoted together by bolts B, passed through said parts, of the curved end standards E, pivoted to the rear cross-bar and 5 extending from there to the front bar, and the curved bar D, clamped to the beam and connected at opposite ends to the front cross-bars by bolts B', which pivotally join the cross-bar and standards together, the several parts be-

ing arranged to operate substantially as and to for the purpose set forth.

In testimony whereof I affix my signature in presence of two witnesses.

ARTHUR MOTT WORD.
